Marin Reiher
ATTORNEY

UNITED STATES PATENT OFFICE.

CARL HELMRICH, OF NEW YORK, N. Y.

TOWEL AND SOAP DISPENSER.

Application filed September 7, 1926. Serial No. 133,830.

This invention relates to dispensers with special reference to those operated only by the insertion of a coin of predetermined value.

5 One of the objects of the invention is to provide a device for dispensing bars of soap adapted to be used in wash rooms of public buildings, etc.

10 A further object is in the provision of means cooperative with a soap dispenser to present an operator with a fresh length of towel with every coin.

15 A still further aim is to provide means to prevent insertion of further coins after the 15 towel supply has been exhausted.

These and other objects, which will appear as the description progresses, are accomplished by the novel construction, combination and arrangement of elements herein- 20 after described and illustrated in the accompanying drawing, forming an important part of this disclosure, and in which:—

Figure 1 is a transverse sectional view showing the arrangement of the elements in 25 accordance with the invention.

Figure 2 is a longitudinal sectional view of the same.

Figure 3 is a fragmentary transverse sectional view showing the coin operated mechanism.

In the drawing, the numeral 10 generally designates a rectangular cabinet having a glass window 11 through which may be viewed any desired advertising displays 12.

35 Journalled in the side walls of the cabinet 10 and extending through at one end is a spindle 13 carrying a roll 14, there being a sprocket wheel 15 mounted thereon over which is trained an operating chain 16 the latter being connected with mechanism (not shown) for actuating the advertising displays 12.

The lower portion of the cabinet contains a right-angled slot 17, the end of which 45 forms a 45 degree angle 18 and vertically slidale in the slot is a spindle 19 carrying a roll 20 on which is wound towelling 21, the same passing over a plurality of idlers 22, the roll 14 and hanging loosely looped 50 below the cabinet.

The other end of the towel is picked up on a roll 14' in the rear of the cabinet and it is kept in order by a guide 15' slidale in a slot 16' in the side walls of the cabinet.

55 Mounted on a flattened portion of the

spindle 13 is a sliding crank 23 containing a spring 24, the head of which abuts against a stop 25 fixed to the cabinet, thus preventing the towel from being promiscuously unrolled.

60 Closely adjacent the cabinet 10 is a metal casing 26 having a vertical elongated portion 27 to receive bars of soap 28.

Journalled in the casing 26 is a rod 29 having a key 30 and on which is mounted a 65 ratchet wheel 31 engaging a pawl 32, the ratchet being adjacent a slotted disc 33 on a line with a second similar disc 34 fixed on a spindle 35, on which is also secured a cam piece 35' to engage the head of the crank 70 23.

The casing 26 contains an opening 36 in register with a pair of guides 37 disposed above the slotted discs 33 and 34.

75 Fixed on the spindle 35 is an arm 38 connected by a link 39 to an ejector 40 normally drawn to the rear by a spring 41 bent around a rod 42.

Projecting into the portion 18 is the end 43 of a curved arm 44 slidale in brackets 80 45 and connected by a link 46 to a cover 47 adapted to close the opening 36 when the towel 21 is completely unwound from the roll 20. The end 43 is connected to the end 85 of the towel, and when the towel has been completely unwound from the roller 20, it pulls on the end 43 to raise the arm 44 to close the opening 36.

Thus, in operation, a coin is dropped in the slot 36. It falls into the slotted disc 90 33. The key 30 is then turned, the coin obviously revolving the slotted disc 34. Therefore the arm 38 pulls the ejector 40 forward causing the lowest bar of soap to drop into an accessible position.

95 The rotation of the spindle 35 also causes the cam 35' to move the crank 23 out of the path of the stop 25. When in such position, the towel 21 may be obviously unrolled from the roll 20 to the roll 14'. Disc 100 34 is held in its advanced position by cam 35' engaging crank 23, and is released when shaft 13 is turned. By pulling on the towel 21, roll 14 and crank 23 are caused to rotate, thus causing further rotation of discs 105 34 and 33 until the coin has reached a point where it will drop from engagement with the discs. The spring 41 then returns the parts to their original position ready to receive another coin.

Having thus described my invention, what I claim as new and desire to secure by Letters Patent, is:—

In a soap dispenser, a casing adapted to contain bars of soap, two spaced shafts mounted parallel therein, a slotted disc fixed to each shaft, said discs being receptive of a coin therebetween, pawl and ratchet means to prevent rotation of one of said

shafts, an arm fixed to the other shaft, an

ejector movable in said casing to dispense the lowermost bar of soap, link connections between said arm and ejector, means for actuating the first named shaft, said means becoming operable upon the insertion of a coin, and means for restoring said arm and ejector upon the passage of a coin from said disc. ¹⁵

In witness whereof I have affixed my signature.

CARL HELMRICH.
